GEORGE A. JOHNSON, OF CHICAGO, ILLINOIS, ASSIGNOR TO WILLIAM H. MINER, OF CHAZY, NEW YORK.

SELF-CENTERING ANTIFRICTION-BEARING.

1,317,793.

Specification of Letters Patent.

Patented Oct. 7, 1919.

Application filed January 29, 1919. Serial No. 273,701.

To all whom it may concern:

Be it known that I, GEORGE A. JOHNSON, a citizen of the United States, residing at Chicago, in the county of Cook and State of Illinois, have invented a certain new and useful Improvement in Self-Centering Anti-friction-Bearings, of which the following is a full, clear, concise, and exact description, reference being had to the accompanying

10 drawings, forming a part of this specification.

This invention relates to improvements in self-centering anti-friction bearings.

One object of this invention is to provide 15 a simple, practical and relatively inexpensive roller bearing especially adapted for railway car side bearings and wherein is employed a minimum number of parts with an anti-friction roller that is self-centering 20 without the aid of springs or other parts likely to get out of order.

More specifically, the object of the invention is to provide an anti-friction roller side bearing for railway cars of a true cylindrical 25 anti-friction roller type possessing all the usual advantages of the true cylindrical roller bearing combined with the self-centering advantages of the usual type of rocker side bearing and without the disadvantages 30 usually accompanying either of said types.

Heretofore it has been customary to employ springs or other means for returning a true anti-friction roller to its central normal position after each actuation of the bearing. 35 and, as is well known, these springs constitute the weakest part of the bearing and often render the bearing unsatisfactory in service in addition to the greater initial cost. In the ordinary rocker bearing, a true 40 rolling action or bodily translation of the antifriction element is not obtained and the return of the rocker to its central position is not always insured. In the device which I have designed, I obtain the true rolling 45 action of a cylinder and effect the return of the roller to its central normal position under the influence of gravity without the aid of any springs or other weak elements and in addition I provide coöperating means 50 on the antifriction element and housing with which it is associated so as to positively maintain proper relation between the anti-friction element and its housing at all times.

55 In the drawing forming a part of this

specification. Figure 1 is a vertical, sectional view of portions of a body and truck bolster of a railway car showing my improvements incorporated in a side bearing interposed between said bolsters. Fig. 2 is a 60 top plan view of the side bearing proper. And Fig. 3 is a vertical, sectional view taken substantially on the line 3—3 of Fig. 1.

In said drawing, 10 denotes the under 65 part of a body bolster of a railway car and 11 the upper part of an opposed truck bolster. In the construction as shown, the side bearing is secured to the truck bolster, said side bearing comprising, broadly, two elements, a housing or casing A and an anti-friction element B.

The housing A is of substantially hollow 70 rectangular formation having end walls 12—12, side walls 13—13, and corner perforated lugs or flanges 14—14 by which the housing is adapted to be riveted to the bolster. At the bottom the housing may be 75 cut away as indicated at 15—15 to permit all dirt or other foreign matter to be readily washed out. On its interior, the housing A is provided with two preferably integral, horizontal flat bearing surfaces 16—16 on opposite sides thereof. These portions of the housing A are separated so 80 as to provide a longitudinally extending opening or recess 17 centrally thereof, as clearly indicated in Fig. 3.

The anti-friction element B, as shown, 85 comprises a true cylindrical section 18 axially cored as indicated at 19, and a depending preferably integrally formed eccentric weighted section 20. The weighted section 20 is located centrally of the roller with respect to its axis, the weighted section 20 normally depending into the recess 17 and being of a slightly lesser width than the recess so that said section 20 coöperates with the adjacent parts of the housing A to prevent any twisting of the anti-friction element 90 within the housing. The ends of the cylindrical section 18 of the element B bear on the surfaces 16 as indicated at 21—21, thus adapting the element B for a true rolling action in either direction from its central 95 normal position. As clearly shown in Fig. 1, the lower edge 22 of the weighted section 20 is made concentric with the surface of the roller section proper 18 and the sides 100 of said weighted section 20 indicated at 110

23—23 are preferably made tangential to the surface of the roller section 18. The dotted lines in Fig. 1 indicate the extreme position of the anti-friction element when 5 actuated to the left as viewed in said figure and it will be evident that the weighted section 20 will be elevated but in no event sufficiently to engage the upper body bolster. Upon release of the actuating pressure from 10 the anti-friction element B, it is evident that the counterweight or weighted section 20 will automatically return the anti-friction element to central normal position under the influence of gravity.

15 In order to hold the anti-friction element in proper assembled relation with the housing A, the element B is provided at each end thereof with annular flanges 24—24 which work within enlarged recesses 25—25 20 provided on the interior faces of the side walls 13 of the housing A. Each of said recesses 25 has an opening 26 at the top thereof to permit insertion of the corresponding flange 24. Each opening 26 is 25 provided at the sides thereof with bendable lips 27—27 which are peened over after the roller is inserted in the housing so as to restrict the width of the openings 26 to an amount less than the diameter of the 30 annular flanges 24. In this manner, accidental removal of the anti-friction element B is positively prevented.

35 In order to insure maintenance of the proper relation between the anti-friction element B and housing A at all times, that is, prevent accidental displacement of the anti-friction element due to vibration or other cause, I provide the following means. The 40 anti-friction element B on each side of the eccentric weighted section 20, is formed with a series of relatively shallow teeth or projections 28. The housing A along the inner edge of each horizontal bearing surface or seat 16 is provided with a corresponding 45 series of recesses 29. With the coöperating sets of teeth 28 and recesses 29, it is evident that the anti-friction element B cannot be shifted by vibration or otherwise, as an entirety, with respect to the housing A unless the element B is rolled in the proper manner. With this construction, the anti-friction 50 element B will always return to its central normal position after each actuation, thus insuring that the element B is in condition to perform its function at all times.

55 The construction herein shown and described is comparatively inexpensive to manufacture, as will be evident since both parts may be readily manufactured in the form of 60 castings; there are no weak parts to get out of order; and accidental displacement of the anti-friction element is positively prevented at all times.

65 Although I have herein shown and described what I now consider the preferred

manner of carrying out my invention, the same is merely illustrative, and I contemplate all changes and modifications that come within the scope of the claims appended hereto.

70

I claim:

1. In an anti-friction bearing of the character described, the combination with a hollow retaining member adapted to be secured to a bolster of a car and having a pair of 75 parallelly arranged, spaced, flat, longitudinally extending bearing seats, of an anti-friction cylindrical roller having its ends adapted to roll along said seats, an eccentrically disposed weight rigid with respect to 80 and projecting radially beyond the periphery of said roller adapted to automatically return the latter to normal position after each actuation upon removal of the actuating pressure, and coöperating projections 85 and recesses on said member and roller arranged to prevent accidental displacement of the roller with respect to said member.

2. In an anti-friction bearing of the character described, the combination with a hollow retaining member adapted to be secured to a bolster of a car and provided with a pair of parallelly arranged, spaced, flat, longitudinally extending bearing seats, of an anti-friction cylindrical roller adapted to 95 have its ends rolled along said seats, said roller having an integrally formed eccentrically disposed weight normally positioned 100 between said seats and adapted to return the roller to normal position after each actuation thereof upon removal of the actuating force, and coöperating projections and recesses on said member and roller arranged to prevent accidental displacement of the roller with respect to said member.

105 3. In an anti-friction bearing of the character described, the combination with a hollow retaining member having a pair of spaced, horizontally extending bearing seats 110 on its interior, and upstanding side walls, the latter being provided on their inner sides with longitudinally extending recesses, of an anti-friction element adapted for rolling movement along said horizontal bearing seats, said element having an integral, normally depending eccentric weight, said element having also end extensions arranged to move within said recesses, said extensions of the element being insertible through vertical openings provided in the side walls of the 115 retaining member and the latter having bendable lips adapted to restrict said vertical openings after the anti-friction element has been assembled with said member, and coöperating projections and recesses 120 on said member and roller arranged to prevent accidental displacement of the roller with respect to said member.

125 4. In an anti-friction bearing of the character described, the combination with a re- 130

taining member, of an anti-friction element, said member having a bearing seat horizontal throughout and on which said element bears and is adapted to roll to either 5 side of normal position, said element having an eccentrically disposed weighted portion rigid with respect thereto and extending beyond the periphery thereof and adapted to be elevated when the element is rolled from 10 its normal position in either direction, and coöoperating interengaging means on the retaining member and anti-friction element adapted to prevent bodily shifting of the anti-friction element with respect to the 15 retaining member but permitting rolling movement of the element.

5. In an anti-friction bearing of the character described, the combination with a base member having spaced, longitudinally ex-

tending bearing seats on its interior, said member having also end walls extending transversely of said seats and adapted to limit the movement of an anti-friction roller, of an anti-friction roller supported at its ends upon said bearing seats, said roller 25 having an eccentrically and integrally formed section normally depending between said seats, a series of teeth on the roller or each side of said depending section, and co-operating series of recesses on the base member, the teeth and recesses preventing bodily displacement of the anti-friction roller with respect to the base member. 30

In witness that I claim the foregoing I have hereunto subscribed my name this 15th 35 day of Jan., 1919.

GEORGE A. JOHNSON.
